UNITED STATES PATENT OFFICE.

JOHN R. O'CONNOR, OF NEWARK, NEW JERSEY.

SCALE-GRINDING MACHINE.

SPECIFICATION forming part of Letters Patent No. 653,937, dated July 17, 1900.

Application filed March 8, 1900. Serial No. 7,474. (No model.)

To all whom it may concern:

Be it known that I, JOHN R. O'CONNOR, a citizen of the United States, residing at Newark, in the county of Essex and State of New Jersey, have invented certain new and useful Improvements in Scale-Grinding Machines; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 The objects of this invention are to facilitate the operation of manufacturing pearl scales for pocket-knife handles, manicure articles, &c., to secure a more even or uniform article, to reduce the cost of manufacture, 20 and to secure other advantages and results some of which may be referred to hereinafter in connection with the description of the working parts.

25 The invention consists in the improved scale-grinding machine and in the arrangements and combinations of parts of the same, all substantially as will be hereinafter set forth, and finally embraced in the clauses of the claim.

30 Referring to the accompanying drawings, in which like letters of reference indicate corresponding parts in each of the several views, Figure 1 is a plan of a portion of the improved scale-grinding machine. Fig. 2 is an elevation of the same. Fig. 3 is a sectional view, 35 taken at line α , Fig. 2, in the direction of the arrow. Fig. 4 is a sectional detail of a certain scale holder or guide; and Fig. 5 is another sectional view of said holder, taken transversely 40 at the bottom of said holder.

In said drawings, a indicates a suitable table, bed, or frame upon which a driving-shaft b is journaled, the journal-boxes c being of any suitable construction. At one extremity of said shaft is arranged a grinding-wheel d , which may be of carborundum, emery, or other material suitable for pearl-grinding. At the inner side of the said wheel, upon the table a , is arranged a bracket or support e . This may be of cast-iron and is adjustable on said table by means of an adjusting-screw f , or any other suitable means, the said bracket

or support being fastened down upon said bed or table by means of bolts g , the adjusting movements being limited or controlled by means of a slideway h and guide-screw i . These devices may be modified to suit any desired construction. At the upper end of said bracket or support e , closely contiguous to the inner side of the wheel d , the said bracket or support is provided with a hinge connection j , on which is fastened a longitudinal slotted scale guide or holder k . This comprises a long piece of steel having on its face next adjacent to the wheel a groove l , Figs. 4 and 5, of a width adapted to receive the scales. Said groove may be of a width sufficient to receive the largest scales commonly used, the smaller scales being held in proper grinding relation by the frictional contact of the wheel holding said scales against one side wall of the groove. The said groove l varies in depth, it being deeper at the top of said holder and more shallow at the lower end, as indicated in broken line in Fig. 2, the graduation, however, being very gradual, so that the pearl is fed very gradually downward toward its place of issue at the lower end. The slow feeding and gradual grinding serves to prevent an overheating and burning of the scale and a consequent reduction in the quality of the pearl. At the lower end of the said scale-holder the same is provided with an adjusting-screw p , whereby the said holder k may be thrown toward or from the flat face of the grinding-wheel d to effect a less or greater thickness in the scale, as may be required, and where the groove l passes out from the side of the wheel I provide across said groove a keeper screw or device m , by means of which the pearl-scale will not be prematurely thrown out of proper parallelism with the scale-holder, and thus injured by the grinding-wheel prior to a complete detachment of said scale from said wheel.

The face of the pearl is first ground by hand or leveled. The leveled piece is then fed into the groove of the scale-holder at the open top, the leveled side lying against the inner face or wall of the groove. The wheel d , working in connection with gravity, causes the scale to pass downward over the inclined face of the guide or holder k against the inner face of the grinding-wheel, and all irregu-

larities are thus removed from the back of the scale, the work being very gradual to prevent heating. When the scale arrives at or near the lower end of the scale-holder, it 5 passes behind the keeper-spring, by which it is held in place in the groove until it is entirely free from the wheel, when it drops by gravity from the grooved scale-holder. Because of the relation of the parts the various 10 scales after having passed through the devices will be of a uniform and regular thickness ready to be applied to the knife-handle or be otherwise applied for use.

By the construction thus described no 15 skilled workmen are required, as heretofore; but a boy simply feeds the leveled plates to the scale-holder, so that a number of such leveled scales are constantly in the said holder subjected to the grinding operation of the 20 wheel.

Having thus described the invention, what I claim as new is—

1. The combination with a grinding-wheel, *d*, of a grooved scale holder or guide *k*, arranged at one side of the said wheel opposite the flat side of said wheel, the groove of which 25 extends vertically downward across the said flat side of said grinding-wheel, the grooved holder being adapted to hold the scales in 30 grinding position while the said scales gravitate across the flat grinding-surfaces of the wheel, substantially as set forth.

2. The combination with the wheel, of a grooved scale-holder, lying opposite the flat

side of the wheel and extending across the 35 flat face of said wheel, and open at the top to receive the scales and at the bottom to permit an exit of the same, substantially as set forth.

3. The combination with the wheel, of a 40 grooved scale-holder, the inner wall of which is inclined to the plane of the side of said wheel, the groove of said holder being open at top and bottom, substantially as set forth.

4. The combination with the wheel, of a 45 grooved scale-holder, the inner wall of the groove of which is inclined, the holder being pivoted to a suitable support at the top and adjustably fastened at the bottom, substantially as set forth.

5. The combination with the frame, table or bed having a grinding-wheel, of the bracket or support *e*, and grooved guide or holder *k*, pivoted to said support at the top and adjustably held at the bottom, substantially as set 55 forth.

6. The combination with the frame, table, or bed having the grinding-wheel, of an adjustable support and an adjustable and grooved guide lying at one side of the said 60 wheel, substantially as set forth.

In testimony that I claim the foregoing I have hereunto set my hand this 24th day of February, 1900.

JOHN R. O'CONNOR.
